COMBINED OPENER AND DISPENSER FOR CANS

Robert L. Perrin, 104 N. Main, McPherson, Kans.

Filed Apr. 3, 1964, Ser. No. 79,337

Term of patent 7 years

(Cl. D58—26)

FIG.1

I claim:

The ornamental design for a combined opener and dispenser for cans, as shown and described.
